UNITED STATES PATENT OFFICE.

GEORGE MILLER MARSHALL, OF LAKE FRANCIS, MANITOBA, CANADA.

MOLD FOR BUILDING-BLOCKS.

1,220,526.

Specification of Letters Patent. Patented Mar. 27, 1917.

Original application filed June 13, 1916, Serial No. 106,940. Divided and this application filed December 6, 1916. Serial No. 135,435.

To all whom it may concern:

Be it known that I, GEORGE M. MARSHALL, at present residing at Lake Francis, in the Province of Manitoba and Dominion of Canada, have invented a new and Improved Mold for Building-Blocks, of which the following is a specification.

My present application is a divisional part of my copending application filed on June 13, 1916, Serial No. 106,940, and my said present invention has for its object to provide a simple, inexpensive and easily manipulated combination of elements adapted for being coöperatively assembled to provide a series of like shaped plastic receiving molds or forms, that are so arranged and combined that a large number of the formed or molded blocks in uniform shape may be expeditiously made at the same time.

With other objects in view that will hereinafter appear, my present invention embodies in a mold for building blocks, certain details of construction and combination of parts, hereinafter explained, specifically pointed out in the appended claims and illustrated in the accompanying drawings, in which:

Figure 1 is a perspective view.

Fig. 2 is a similar view, on an enlarged scale, of a portion of my present form of mold, some of the mold pockets being shown empty and parts being shown in section.

Fig. 3 is a transverse section thereof on the line 3—3 on Fig. 2.

Fig. 4 is a similar view on the line 4—4 on Fig. 2.

Fig. 5 is a perspective view of one of the end plates.

Fig. 6 is a cross section thereof on the line 6—6 on Fig. 5.

Fig. 7 is a perspective view of one of the side plates.

Fig. 8 is a cross section on the line 8—8 on Fig. 7.

Fig. 9 is a horizontal section of a portion of one of the end plates and the coöperating ends of two side plates.

Fig. 10 is a perspective view of one of the blocks made by my construction of mold.

Fig. 11 is a similar view looking at the opposite side from that shown in Fig. 10, and

Fig. 12 illustrates a portion of a wall structure embodying the form of block made by my present construction of mold.

In my present construction of mold for forming building blocks, a main frame is provided that consists of a pair of oppositely disposed angled or side bars 1 and 2, to the ends of which are secured, by rods 8 and 9, anchor plates 4—5—6 and 7 that extend above the vertical portions of the members 1 and 2.

The anchor plates have slots for receiving the ends of tie rods or bolts 8 and 9, one at each end of the mold, and each of which, at one end, has a head 10 and the other end threaded for receiving a clamp nut 11, as is clearly illustrated in Figs. 1 and 2, by reference to which it will be seen that when the rods 8 and 9 are operatively adjusted, by screwing up the nuts 11—11, the angled side bars 1 and 2 of the carrying or main frame, are drawn up for holding the mold pocket forming elements together, as is clearly shown in Fig. 1.

Angled bars 13, 14, 15 and 16 are fixedly attached, by rivets 12, to each end of the angled bars 1 and 2 and the said members 13, 14, 15 and 16, with the angled bars 1 and 2, the slotted angled members 4, 5, 6, and 7 and the tie rods 9 and 8, form the complete carrying frame before referred to.

17—17 designate sole or supporting plates that extend transversely with respect to the side bars 1 and 2 and have their ends resting upon the horizontally flanged portions of the said angled members 1 and 2.

In the present showing, the carrying frame is designed to accommodate a number of molds, arranged in rows of six in length, and in such arrangement, I employ seven sole plates, the end ones 17^a—17^a of which are comparatively narrow while the intermediate ones are relatively wide.

18 designates bottom plates, hereinafter termed pallets, each of which is of a width and length of the building block to be formed and, the said pallets 18, are mounted upon the sole plates in parallel, longitudinal and transverse rows with the sides and ends spaced a short distance apart, as is clearly shown in Figs. 3 and 4, and for the purposes presently explained.

In the drawing (Fig. 1) is shown thirty pallets, supported on the carrying frame, but I desire it understood the number of the pallets may be more or less, in accordance with the sizes of the blocks to be molded. The sides and ends of the mold pockets are

formed by end plates 19 and side or partition plates 20 and both the end and side plates have their lower edges seated upon the sole plates or members 17—17^a and located in the spaces ⁵ ⁷⁰ that intervene the assembled pallets, it being understood that the outermost ones of the end and side plates also rest on the sole plate 17 and embrace the outermost edge of the outermost ones of the side and end pallets, as is clearly shown in Figs. 3 and 4, by reference to which it will also be noticed that the side plates 20 are in the nature of stout spacing or partition members having the length of the block to be formed while the end plates extend entirely across from one side bar to the other side bar of the carrying frame, extending, as it were, the full length of the transverse sets of blocks, and with the ends of the side plates or sections 20 interlockably abutting the end plates, as hereinafter more fully explained.

The end plate 19 in my present construction, at a short distance from its upper edge, ²⁵ has a plurality of similar shaped alining tongues 31, V-shaped in cross section, with the ends of adjacent ones of the said tongues 31 spaced apart a distance equal to the thickness of the partition or side plates 20, and the tongues 31 at one end are beveled or tapered as indicated at 22, while the other end terminates in a straight or upright surface indicated by 34, as best shown in Figs. 5 and 9, by reference to which it will be seen ³⁵ that the straight edge 34 of one tongue is adjacent the beveled end 22 of another tongue.

The V-shaped grooves 32 in the end plate have both their ends terminating in abrupt or right-angled walls 32^a, as is clearly shown ⁴⁰ in Fig. 9.

Each side or partition plate 20, that cooperates with the end plates, hereinbefore described, has a continuous longitudinally disposed V-shaped tongue 35 at one side, one ⁴⁵ end of which is tapered as at 36, and, on the other side, it has a longitudinally disposed V-shaped groove 37, one end of which terminates short of one end of the plate, as indicated at 38.

⁵⁰ Centrally of the length of the groove 37 is an elongated filler portion 39 and, on that side having the said filler 39, the plate 20 has a laterally projected V-shaped slot forming web 40 whose upper edge is flushed with the upper edge of the plate, as shown.

From the foregoing taken in connection with the drawings, the complete construction and the manner in which the several parts that constitute my present construction of mold are assembled for use, will be readily understood by those skilled in the art to which my invention relates.

In the use of my present invention, the mold is set up by beginning at any corner of ⁶⁵ the carrying frame and first placing an end

plate crosswise between the side bars of the said frame and resting them on the sole plates supported by the said side bars, after which a side plate is placed upon the sole plates and positioned against an adjacent side portion 1 of the carrying frame with the end thereof abutting the previously set end plate. A pallet 18 is then placed, with two of its opposite edges bearing on two adjacent sole plates and with the other two of its edges bearing against the previously set end and side plates. ⁷⁵

Another side plate is then placed upon the sole plates with its ends abutting the opposite pair of end plates, the said ends of the side plate being rigidly held in place by fitting between the tongues 31 on the said end plates. ⁸⁰

Another pallet 18 is then placed in position with its edges bearing against the adjacent set side plate and the opposite end plates, after which another side plate is set up and so on. ⁸⁵

By having machined pallets within the mold pockets engaging the side and end plates, as stated, a rigid mold structure is provided and when the parts are assembled in the manner stated one that will produce absolutely rectangular or square blocks without the slightest trouble to the operator. ⁹⁰

In Figs. 10 and 11, I have shown a complete block made by my present construction of mold forms and the said block, it will be noticed, has a continuous V-shaped groove on one side and one end and a projecting V-shaped tongue on the other end and the other side has a V-shaped tongue extending along its face which has a recessed channel and a transverse slot that passes from the channel diagonally across the adjacent corner of the ¹⁰⁰ block.

To explain—the tongues and grooves of the block formed by my present construction of mold are made by the tongues and grooves of the side and end plates, the cross channel ¹¹⁰ *f* is made by the filler portion 39 on the side plate and the slot *g* is produced by the V-shaped web 40 that projects from the portion 39 of the said side plate.

In the operation of making a nest of ¹¹⁵ blocks, after the mold forms have been properly positioned, a self-binding surfacing material is run into the mold pockets and then a self-hardening body or backing material is filled up to the level or upper edges of the ¹²⁰ mold members and around the tongue members and into the grooves, after which the filled mold is allowed to set and when set, the entire mold may be readily separated by releasing the tie bolts at the opposite ends ¹²⁵ thereof.

By reason of the peculiar formation of the blocks made by my present construction of mold, they can be readily assembled in constructing a wall or partition and secured to ¹³⁰

the angled uprights or guides in the manner clearly shown in Fig. 12, in which the said blocks are shown tied to the said uprights by nail or rod clips 80 that have their opposite 5 ends bent at right angles and in opposite directions, whereby when applied for use, one of the ends laps over one edge of the uprights and the other end extends laterally of the slot *g* and lies flatwise on the cross 10 channel *f*, it being understood that when the next block is placed in position, the clips 80 are firmly embedded in the wall and tied to the uprights.

What I claim is:

15 1. A mold of the class described having a series of longitudinally extending side mold plates, transversely extending end mold plates, each of the said side plates being provided with V-shaped tongues and V-shaped 20 grooves, a filler located in the said groove and a slot forming web carried by the said filler.

25 2. A mold of the class described having a pair of transversely extending end mold plates, a series of longitudinally extending side mold plates located between the end plates, each of the said side mold plates having a V-shaped tongue and a V-shaped 30 groove, a filler piece in the groove and a slot forming web projected laterally from the filler piece of the said side plate.

3. In a mold of the class described, the

combination with a plurality of transverse or end mold plates; of a plurality of side mold plates, said side mold plates each including a filler piece and a laterally projected angular extension adapted for forming a slot across one edge of a block when formed in the mold.

4. In a mold of the character stated, a 40 plurality of end plates, a plurality of side plates located between the end plates, the said side and end plates being removably sustained on the supporting frame, the end plates having a series of separated alining 45 V-shaped tongues at one side, each tongue having one end terminating in a straight edge and the other edge terminating in a beveled edge, a series of corresponding V-shaped grooves on the other side of the said end plates whose ends terminate in straight edges, said side plates having a tongue on one face that extends from one end to a point near the other end and terminates in a 50 beveled edge and a corresponding groove on the other face having the ends thereof terminating in straight edges, the groove having a filler portion that forms a channel in the tongue and a V-shaped web that projects laterally from the filler portion, and means 55 for holding the frame and the mold pocket 60 forming elements in rigid relation.

GEORGE MILLER MARSHALL.
